HEATING APPARATUS FOR AIRCRAFT OR
THE LIKEWilliam E. Huffman and George W. Replogle,
Dayton, OhioOriginal application June 6, 1933, Serial No.
674,556. Divided and this application October
10, 1939, Serial No. 298,806

13 Claims. (Cl. 237—12.3)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to apparatus for heating the interior of a vehicle body, such as cabins of aircraft, automobiles, and the like. The device relates particularly to a vapor heating system in which a vapor generator is operatively associated with the exhaust system of the internal combustion engine driving the vehicle, to utilize the heat from the exhaust gases for operating the generator. The generated vapor is passed through a suitable radiator placed in the interior of the vehicle.

It is an object of this invention to provide a vapor heating system of a non-pressure type, in which pressure or heat-controlling devices are not required and in which the rate of vapor generation is controlled by automatically varying the quantity of liquid in the generator instead of varying the quantity of heat to the boiler.

It is a further object of this invention to provide a heating system in which the quantity of liquid in the boiler is continuously and automatically reduced or totally displaced by vapor when a greater quantity of vapor is generated than can be condensed by the radiator.

A further object of this invention is to provide a low pressure vapor generator associated with the exhaust manifold of the internal combustion engine of the vehicle, a radiator unit operatively connected to the generator for effecting a forced radiation of heat received therefrom, and a condensing unit operatively connected to the radiator and the generator for the purpose of condensing vapor fluid received from the radiator and permit the return flow of condensed liquid into the generator.

A still further object of this invention is to provide in a heating system of this character, a radiator having metering means so located with respect thereto that as liquid in the boiler is heated to the boiling point and passed into the radiator, it is permitted to pass into the condensing unit in a prearranged controllable amount. This permits the forcing of liquid from the boiler into the condenser when sufficient back pressure has been built up in the radiator to overcome the static head in the condenser. It is possible, by thus utilizing the back pressure, to force all the liquid from the boiler, thus automatically permitting only sufficient liquid to remain in the boiler to generate the amount of steam required.

This application is a division of application Serial No. 674,556, filed June 6, 1933, and relates to the subject matter disclosed therein, which is particularly, although not exclusively, adapted for use in instances where the radiator is positioned below the boiler and condenser units.

Figure 1 of the drawing diagrammatically illustrates a generator, radiator, condenser, and appurtenant structure.

10 Figure 2 is a sectional view from the left through the exhaust pipe showing an elevational end view of the boiler;

Figure 3 is a modified type of boiler;

Figure 4 is an end view of Figure 3.

15 Referring to the drawing, B refers generally to the boiler or generator; C, to the condenser-reservoir unit; and R, to the radiator.

The generator is operatively connected to the radiator by tube 15'. The condenser is connected to the bottom of the radiator by tube 57 and to the top of the radiator by tube 16'. The condenser-reservoir unit is communicatively connected to the generator by tubes 17, 29 and passageway 28.

20 25 Generally speaking, heat conveying vapor is generated in the boiler and conducted to the radiator placed in the interior of the compartment to be heated. The condenser and reservoir unit functions to maintain a supply of fluid to the generator and to receive condensate fluid from the radiator when the radiator becomes filled with steam or vapor under pressure. The condenser unit also functions to prevent escape of vapor and acts as a relief valve to prevent the building up of a dangerous pressure.

30 35 The generator B comprises a member 18 inserted in and connected to an exhaust line 19. Contained within member 18 is a boiler or generator 21 in the shape of a wedge having parallel, generally triangular-shaped faces and a base in uppermost position. The lower portion of the wedge comprises a reservoir 22 for the unvaporized fluid and a plug 2' for emptying the reservoir. Overflow tube 24, controlled by valve 25, serves to control the level of fluid in the generator.

40 45 The generator is provided with a plugged filling inlet 23; an opening 27 for allowing passage of vapor from the generator to the radiator; a tube 27' for returning the condensed vapor from tube 15' directly to the reservoir; and a tube 29 having an opening portion 28 operatively engaging tube 17 for directly connecting the condenser with the reservoir portion of the generator.

50 55 The condenser and reservoir unit C is provided

with a reservoir portion 12; a condenser portion 12'; a spring operated flap valve 53 adjacent the bottom of the reservoir portion and adapted to open upon a predetermined pressure difference; a vent 45 adjacent the top of the condenser; and a by-pass line 50' having therein a pre-calibrated spring controlled check valve 52.

The radiator R comprises the usual radiating fins 11' and heat-distributing fan 59 in addition to the header tank or sump 34'. Valve 51 in sump 34' comprises ball valve 56, upper valve seat 54 and lower valve seat 55.

The header tank is provided with a member 36 having valve seat 54 and openings 35. Openings 35 permit equalization of pressure between the sump and radiator and prevents ball 56 from sticking in the closed position. Adjacent the upper end of the radiator is a valve 46 for permitting the flow of uncondensed steam to the condenser and also for the purpose of providing an outlet for air which may have been trapped in the radiator. The valve seat serves as a metering orifice to regulate the return of uncondensed steam directly to the condenser unit.

In the operation of the device, heated vapor generated in the boiler 21 by the hot gases from exhaust pipe 19 passes through opening 21 and tube 15 to sump 34' and thence into the radiator through opening 54. Valve means 46 may be closed or may be opened to permit flow to the condenser of any air that may have been trapped in the radiator and also to permit the return of a metered amount of uncondensed vapor directly to the condenser. The hot vapors are condensed in the radiator and the condensate will collect in the sump 34' until the sump is full, at which time ball valve 56 will seat in opening 54, preventing condensed liquid from being forced up into the radiator. Sump inlet 13' is now temporarily closed off, continued heating of the vapor will establish a pressure which will force the condensed fluid in the sump into the pipe 57 toward the condenser unit. This lowers the ball 56, allowing more steam to enter the radiator and consequently more condensate to flow to the sump and the action is repeated until all the fluid in the generator sump has been vaporized or until the remaining unvaporized liquid is forced by vapor pressure into tubes 29 and 17, or even into the condenser by way of by-pass 50' and valve 52, should the pressure become large enough to overcome the spring holding valve 52 in place. Flap valve 53 prevents return of fluid directly to the condenser and permits the building up of sufficient pressure to force the condensate from the sump 34' through conduit 57 into the condenser. The nature of construction of the valve 56 and seat 55 is such that vapor under pressure will force past valve 56 to conduit 57 to force the condensed fluid from sump 34' through tube 57 into condenser unit C.

In order to prevent the generator unit from standing with condensate in the radiator sump, valve 46 is closed and the device operated until the condensate is forced into the condenser unit. If the liquid becomes frozen in the generator sump or the condenser, it is readily appreciated that the frozen liquid will be easily thawed out due to the proximity of these units to the hot exhaust gases. A thawing of the radiator and radiator sump on the other hand would, under most circumstances, be a difficult and laborious proposition.

The boiler 65 which is shown connected to the exhaust manifold of the engine is better illus-

trated in Figures 3 and 4. As shown in these figures, this boiler is provided with a circular portion 66 forming an inner casing which is adapted to be connected to the exhaust manifold of the engine. An outer casing 67 of cylindrical cross section and forming a main boiler is adapted to be suitably welded or otherwise secured to the inner portion 66 of the boiler. By observing Figures 3 and 4 it will be noted that an auxiliary boiler unit 68 is provided which is mounted within the inner circular casing 66 of the boiler herefore mentioned. This auxiliary boiler is connected at its upper and lower end to the main boiler 67 through the medium of connecting lines 69 and 70. As shown in Figure 4 this auxiliary boiler is comparatively small in cross sectional area; consequently, the amount of water retained therein is substantially small. By providing an auxiliary boiler in the manner set forth, it will be apparent that when the motor is started the exhaust gases in passing around the auxiliary boiler will immediately heat the water in the boiler to boiling point and a generation of steam will be effected in a very short period of time.

The invention is not intended to be limited to the specific form shown in the drawing and described in the detailed description, it being understood that the invention is susceptible of various modifications and alternative constructions that fall within the spirit and scope of the invention as expressed in the appended claims.

We claim:

1. In a heating system, a steam generator, a radiator including an inlet and an outlet orifice, the former having an effective cross-sectional area sufficiently large to permit the steam to enter said radiator in quantities in excess of the condensing capacity thereof, means connecting said generator to the inlet orifice of said radiator a condenser unit operatively connected to said generator and including a reservoir connected to the outlet orifice of said radiator and positioned above said steam generator and radiator for receiving and condensing the excess of steam from said radiator and permit gravitational flow of the same when condensed into said steam generator, the effective cross-sectional area of said outlet orifice being less than the effective cross-sectional area of said inlet orifice to restrict the passage of excess steam from said radiator and establish a back pressure therein, and float controlled means cooperating with said radiator for obtaining a discharge of the condensate in said radiator to said condenser unit when the float in said means assumes a predetermined position.

2. In a heating system, a steam generator, a radiator including an inlet and an outlet orifice, the former having an effective cross-sectional area sufficiently large to permit the steam to enter said radiator in quantities in excess of the condensing capacity thereof, means connecting said generator to the inlet orifice of said radiator a condenser unit operatively connected to said generator and including a reservoir connected to the outlet orifice of said radiator and positioned above said steam generator and radiator for receiving and condensing the excess of steam from said radiator and permit gravitational flow of the same when condensed into said steam generator, the effective cross-sectional area of said outlet orifice being less than the effective cross-sectional area of said inlet orifice to restrict the passage of excess steam from said radiator and establish a back pressure therein, and means in the lower end of said radiator for automatically returning

in successive stages the condensed steam in said radiator into said condenser unit.

3. In a heating system, a steam generator, a radiator including an inlet and an outlet orifice, the former having an effective cross-sectional area sufficiently large to permit the steam to enter said radiator in quantities in excess of the condensing capacity thereof, means connecting said generator to the inlet orifice of said radiator a condenser unit operatively connected to said generator and including a reservoir connected to the outlet orifice of said radiator and positioned above said steam generator and radiator for receiving and condensing the excess of the steam from said radiator and permit gravitational flow of the same when condensed into said steam generator, the effective cross-sectional area of said outlet orifice being less than the effective cross-sectional area of said inlet orifice to restrict the passage of excess steam from said radiator and establish a back pressure therein, the lower end of said radiator being provided with a header tank connected to the reservoir of said condenser unit, a two-way ball check valve in said header tank adapted for selectively controlling the passage of the steam into said radiator or utilize said steam pressure to effect a discharge of the condensed steam in said header tank into said condenser unit.

4. A radiator including a core through which a heating fluid is caused to travel, an upper and a lower header on the opposite end of said core, the upper header including an outlet orifice, the lower header being provided with an inlet orifice, a manually adjustable metering device in said outlet orifice for restricting, in predetermined amounts, the passage of the heating fluid therethrough, the lower header being provided with an auxiliary port to permit the discharge therethrough of the condensed heating fluid and a ball check valve for controlling the opening and closing of said port.

5. A vapor generator comprising, a casing adapted for being connected with the exhaust pipe of an internal combustion engine, a boiler in said casing within which a liquid to be evaporated is received, said boiler being in the form of a wedge with two parallel, generally triangular-shaped faces and a base in uppermost position, the lower portion of said boiler constituting a sump portion, an outlet pipe for the evaporated liquid located adjacent the upper portion of said boiler, and an inlet pipe having its lower end disposed in the sump of said boiler.

6. A vapor generator as set forth in claim 5, the sump portion of said boiler being characterized by being disposed outside the zone of heat of said casing to prevent surging of liquid discharged through said inlet pipe and thereby stabilize the level of the liquid.

7. A vapor generator comprising, a casing adapted for being connected to the exhaust pipe of an internal combustion engine, a boiler in said casing within which a liquid to be evaporated is received, said boiler being provided with a sump portion at its lower end, an outlet pipe for the discharge of evaporated liquid mounted in the upper end of said boiler, an inlet pipe having its discharge opening disposed in the sump portion of said boiler, a liquid trap positioned in said outlet pipe, and a drain pipe leading from said trap into the sump portion of said boiler adapted for receiving and conveying condensed liquid in said outlet pipe into the sump portion of said boiler.

8. A vapor generator comprising, an outer cas-

ing, an inner casing within said outer casing adapted for being connected to the exhaust pipe of an internal combustion engine, the effective cross-sectional area of said inner casing being substantially equal to the effective cross-sectional area of said exhaust pipe to receive a maximum of heat therefrom, the outer casing forming a main boiler within which the liquid to be evaporated is adapted for being received, and an auxiliary boiler communicatively connected to said first mentioned boiler and disposed within said inner casing to obtain an instantaneous generation of vapor of the liquid contained therein.

9. A vapor generator comprising an outer casing, an inner casing within said outer casing adapted for being connected to the exhaust pipe of an internal combustion engine, the effective cross-sectional area of said inner casing being substantially equal to the effective cross-sectional area of said exhaust pipe to receive a maximum of heat therefrom, the outer casing forming a main boiler within which a liquid to be evaporated is adapted for being received, and an auxiliary boiler communicatively connected to said first mentioned boiler and disposed within said inner casing, the heating surface of said auxiliary boiler being small as compared to the heating surface of said outer casing to thereby obtain an instantaneous generation of the vapor of the liquid contained therein.

10. In combination, a vapor generator adapted to receive a vaporizable fluid and associated with the exhaust pipe of an internal combustion engine to be heated by the exhaust gases passing therethrough, a reservoir above said generator and communicatively connected therewith, a one-way valve for controlling flow of fluid from said reservoir to said generator, a radiator below said generator, a condensate collecting chamber communicatively connected with said radiator and in series with said generator and said reservoir and valve means in said chamber operatively associated with the connection of said chamber and radiator and responsive to the condition of the fluid in the chamber for controlling the flow of vapor to said radiator and condensate to said reservoir.

11. A vapor heating system for a vehicle driven by an internal combustion motor comprising a vapor generator adapted to contain a vaporizable liquid and associated with the exhaust pipe of said motor to be heated by the exhaust gases passing therethrough, a radiator positioned in said vehicle below said generator, a condenser-reservoir unit operatively connected to said generator for supplying vaporizable fluid to said generator, means for preventing return of fluid directly from said generator to said reservoir, means communicatively connecting said generator to said radiator for the passage of vapor thereto, condensate receiving means communicatively connected to said radiator and to said condenser-reservoir unit and means operatively associated with said condensate receiving means and responsive to the accumulation of a predetermined amount of condensate in said condensate receiving means for controlling return of condensate to said condenser-reservoir unit.

12. A vapor heating system for a vehicle driven by an internal combustion engine comprising a vapor generator adapted to contain a vaporizable liquid and associated with the exhaust pipe of said motor so as to be heated by the exhaust gases passing therethrough, a radiator positioned in said vehicle with the lower portion thereof be-

low said generator, a vented condenser-reservoir unit operatively connected to said generator for supplying vaporizable fluid to said generator, valve means in said condenser-reservoir unit for preventing return of liquid and/or vapor from said generator to said condenser-reservoir unit, pressure relief means associated with the connection between the generator and the condenser-reservoir unit, conduit means for conveying vapor from said generator to said radiator, sump means communicatively connected with said condenser-reservoir unit and operatively associated with said radiator and said last named conduit means for collecting condensate from said radiator, valve means in said sump for controlling the accumulation of condensate therein, said last named valve means controlling the flow of vapor to said radiator so as to utilize the vapor pressure for returning condensate to said reservoir.

13. A vapor heating system for a vehicle driven by an internal combustion engine comprising a vapor generator adapted to contain vaporizable liquid and associated with the exhaust pipe of said motor so as to be heated by the exhaust

5 gases passing therethrough, a radiator communicatively connected with said generator and positioned in said vehicle with the lower portion of said radiator below said generator, a vented condenser-reservoir unit communicatively connected with said generator and said radiator for supplying fluid to said generator and receiving condensate and/or vapor from said radiator, valve means in said condenser-reservoir unit for preventing return of liquid and/or vapor from said generator to said condenser-reservoir unit, pressure relief means associated with the connection between the generator and the condenser-reservoir unit, condensate accumulation sump means 10 associated with said radiator, conduit means connecting said generator with said sump means for conveying vapor to said radiator, valve means in said sump means operative upon the accumulation of a predetermined amount of condensate in 15 said sump means to prevent flow of vapor to said radiator thereby enabling vapor pressure to return condensate from said sump to said condenser-reservoir unit.
